SUBCALIBER AUXILIARY BARREL AND EXTRACTOR

William Summerbell, Washington, D. C.

Application April 26, 1944, Serial No. 532,739

2 Claims. (Cl. 89—29)

(Granted under the act of March 3, 1883, as amended April 30, 1928; 370 O. G. 757)

1

The invention described herein may be manufactured and used by or for the Government for governmental purposes without the payment to me of any royalty thereon.

The invention relates to subcaliber guns and has for an object to effect improvements looking to the better performance of the subcaliber ammunition and at the same time to save the major caliber tube from wear, corrosion, or fouling in any way incident to the use of the smaller caliber ammunition. This is important, since practice firing with smaller than standard ammunition must often be carried on extensively and over extended periods of time, and instruction would be greatly impaired by necessity for cleaning the larger gun frequently. There has been a deficiency in satisfactory subcaliber equipment of this kind, and particularly for the current models of 75 mm. and larger guns.

An important purpose is to enable the functioning of the standard breech block, firing mechanism and semiautomatic breech closing mechanisms with the subcaliber ammunition.

A further important aim is to accomplish effective extraction of subcaliber cartridge cases by functioning of the regular extractor mechanism.

It is one of the objects of the invention to present a subcaliber auxiliary tube and extractor which is readily applicable to different models of guns without structural modification of the latter, or tooling of any kind thereon; as well as to avoid marring surface finish.

An impelling motive prompting the evolution of the invention is the need of such equipment which may be applied without disassembly or structural modification of the gun on which it is to be used, while at the same time attaining all the essential benefits of economy, accuracy of fire, and otherwise, as indicated.

A special end in view is to enable rapid and effective conversion of "tank guns" to smaller caliber with the above mentioned advantages.

In prior attempts to provide subcaliber adapters for large caliber guns difficulty has been experienced due to dissipation of the force developed by the propellant and it is an object of this invention to reduce such losses to a minimum.

One factor in such dissipation of force is friction of the projectile upon the subcaliber barrel.

Additional objects, advantages, and features of invention are involved in the construction, arrangement, and combination of parts involved in the embodiment of the invention, as may appear or be understood from the following description and accompanying drawings, wherein:

2

Figure 1 is a longitudinal vertical section of a 75 mm. gun tube now largely in use, equipped with my invention, sections of the tube being omitted at intervals, forwardly of the chamber;

Figure 2 is a rear elevation of the breech end of a 75 mm. gun on which my invention is incorporated, and showing the extractors of the conventional breech mechanism;

Figure 3 is a section on the line 3—3 of Fig. 1; Figure 4 is a rear elevation of the subcaliber tube alone;

Figure 5 is a fragmentary elevation of the breech end of the subcaliber tube alone;

Figure 6 is a rear view of the subcaliber ejector alone;

Figure 7 is a side view thereof;

Figure 8 is a rear elevation of the anchor block alone;

Figures 9 and 10 are, respectively, a bottom view and a side view of the anchor block.

Reference is made to Patent No. 1,393,353, Oct. 11, 1921, L. L. Driggs; and No. 1,802,727, April 28, 1931, to G. M. McCann, for an understanding of the extractor devices referred to hereinafter.

Referring more particularly to the drawings, there is illustrated a 75 mm. gun tube 10, which is unchanged from that heretofore used in so-called tank guns (by which is meant guns for mounting in the turrets of armored vehicles known as

30 "tanks"). This tube includes the usual smooth-bored chamber 11 shaped to receive cartridge rounds and including also the shoulder 12 and rifled bore 13 (representation of the rifling being omitted in the drawing). The chamber opens

35 flush through the planiform breech face of the tube which is normal to the axis of the tube. The tube is customarily formed with external threads 14 at its rear end, which are screwed into a breech ring 15. Upon the ring 15 there

40 is mounted a breech block 16, its operating mechanism, and a firing mechanism, but as these are unchanged for operation with my invention, and are not directly connected therewith except for a contact by the extractors 17, they are not illus-

45 trated, and no detailed description thereof need be given here, only the extractors being referred to and illustrated.

A subcaliber barrel including a rifled tube 20 is shown, which has been made in conformity with 50 a standard 37 mm. gun tube as to diameter of its chamber portion 21, and its bore portion 22. But the length is materially shortened in the present instance (particularly to enable its mounting in a tank gun in situ in the tank), although this 55 length may be varied as expediency may dictate,

for use in other larger caliber guns. At its rear end the material at the top of the tube 20 is cut away horizontally to a depth of somewhat less than one-half the thickness of the chamber wall of the tube and from its butt face 23 a very short distance forwardly, leaving an upstanding transverse rectangular rib 24 near the breech of the tube, and a groove 25 beside the rib at its forward side. A jacket 26 forming part of the subcaliber barrel is shrunk on the rear part of the tube 20, of a size exteriorly to fit the wall of the chamber 11 and cut away to conform to the cut away part of the tube 20 at the groove 25. From the jacket to near its forward extremity the tube 20 is tapered to a minimum thickness. The tapering is excepted near the forward end of the tube where a cylindrical, externally threaded part 27 is formed, on to which there is screwed an adapter ring 28, tightly fitting the subcaliber tube, and also fitted to the bore of the tube 10 just beyond the forcing shoulder or cone 12.

A lock block or anchor block 29 is set against the rear face of the tube 10, consisting of a planiform plate 30 having a thickness approximating that of the conventional extractors, of a length to extend horizontally across the breech face of the tube within the breech recess of the breech ring, and extending from the level of the base of the rib 24 to a distance above the opening of the chamber 11. A forward block segment extension 31 is formed integrally with the plate 30, its lower face 32 in a plane with the lower edge of the plate 30 and its upper side 33 conforming to the arc of the chamber 11, and correspondingly slightly tapered to fit into the chamber. The lower side 32 of this block is substantially planiform, and its thickness in the segment portion is somewhat greater than the longitudinal extent of the cut away part of the tube 20 adjacent the rib 24. At a distance from the inner face of the segment corresponding to the width of the groove 25 longitudinally of the tube 20, a groove 34 is formed in the under face 32 of the block 29, to fit the rib 24.

With the block 29 thus fitted to the tube 20, the tube may be thrust forwardly in the large caliber tube 10 until the jacket 26 fits the chamber 11 and the ring 28 fits the bore or lands of the tube 10 as in Fig. 1. The extreme forward end of the tube 20 is cylindrical and externally threaded as at 36, and screwed thereonto is an internally threaded anchor tube 35, cylindrical, and of uniform thickness throughout, its internal diameter being much greater than that of the barrel 20. This tube 35 is extended beyond the muzzle of the tube 10, and there provided with a seat or anchor ring 37, fitted snugly to the tube 35, and in the bore of the larger gun a distance as a bushing. A set screw 38 is engaged through the ring 37 against the tube 35, but the two may be otherwise secured together. The ring 37 is enlarged before the end of the tube 10 to afford a shoulder 39 set against the muzzle end of the tube 10 with an interposed gasket 40. Sockets 41 are shown in the outer face of the ring 37 permitting application of a spanner wrench thereto to screw the tube 35 onto the barrel tube 20.

Any desired number of support bushings 42 may be secured on the tube 25 spaced longitudinally thereon and fitting the bore of the tube 10.

When the tube 20 is assembled on the tube 10, and drawn in with the block 29 snug against the breech face of the tube 10, the butt face 23 of the tube 20 is set slightly to the rear of the plane

of the breech face of the tube 10. It happens that the rear face of the rib 24 at this time is alined with the breech face of the tube 20.

The tube jacket 26 is relieved externally 5 throughout its major rear portion to a forward shoulder 43, to form a cylindrical surface 44, the remaining forward part 45 of the jacket being the full diameter of the chamber 11 and fitting the same as a bearing of good width supporting the inserted tube 20.

An extractor sleeve 46 is fitted slidably around the relieved part 44 of the jacket 26, this sleeve conforming exteriorly somewhat to the shape and size of the butt end portion of a cartridge case 15 of the kind conventionally used in full caliber size in the tube 10, but being preferably made of steel.

The sleeve 46 is tapered externally to fit the chamber 11 from the bearing part 45 of the jacket 26 to the mouth of the chamber, but is 20 slotted on its upper side as at 47 (Figs. 6 and 7) over an angle slightly more than that included by the junctions of the lower face of the block 29 and wall of the chamber 11 so that the block sets free across the slot 47. This permits the 25 sleeve to slide rearward from a loaded forward position to a rear discharge position nearly two calibers of the tube 10 from the loaded position in the instance illustrated.

The sleeve has an integral head 48 and peripheral flange 49, the head being of such shape and thickness that at full forward or loaded position of the sleeve it is nearly or quite in contact with the butt faces of the tube 20 and jacket 26, and the flange 49 lies spaced from the breech face of the tube 10 in the same degree as would the extractor flange or rim of the conventional cartridge case of a full caliber round loaded in the larger caliber gun. The rear face of the head 48 is planiform, and in or slightly rearward of the 40 plane of the rear face of the block 29 when the sleeve 46 is at forward or loaded position.

By reason of the size, shape, and proportions of the sleeve 46 as thus described, it is able to function with, and be operated by, the extractors 17 45 of the regular breech mechanism of the larger caliber gun of which the tube 10 forms a part. It will be apparent that it would also function with other extractor mechanism or device for engaging conventional extractor rims on cartridges of the 50 larger size.

The head 48 is formed with a concentric opening 50, of the same diameter as, and alined with, the chamber 21, and this opening is rabbeted at the rear as at 51, to receive the usual extractor 55 flange of the smaller caliber cartridge case when such a round is inserted in the chamber 21, so that the rear face of the head of the smaller caliber case will set at or slightly to the rear of the plane of the rear face of the extractor head 48 60 when the parts are at full loaded position. This permits the forward face of the breech block of the standard breech mechanism of the larger caliber weapon to set against the head of the sub-caliber cartridge case when the block is operated 65 normally—that is, by the reaction of the regular closing spring—after the breech has been opened manually by the standard operating handle forming a permanent part of the conventional breech mechanism, these features being well known and understood.

Also, as a consequence of the inter-operative relation of the structure of my invention, the subcaliber ammunition, and the breech mechanism, the standard firing mechanism of the larger caliber gun will function conventionally with the 75

subcaliber rounds, the primer of the smaller caliber cartridge being alined with the firing pin of the regular breech block when the latter is closed.

The several features pointed out obviate the need for any special mechanism whatever in order to fire subcaliber ammunition when using my invention, and the only departure from usual full caliber operation, after my subcaliber chamber and barrel are put in place, is that the breech must be opened manually, due to the lack of sufficient recoil from firing of the subcaliber ammunition.

In use, guns such as the 75 mm., and larger and smaller caliber weapons using the same type of breech closure, may be equipped with my subcaliber tube and operated as last above mentioned, and it is believed applicable to use with other breech structure, including the rotating block type.

The application of the subcaliber chamber and barrel, and firing of the subcaliber ammunition are effected without alteration of structure or use of attaching bolts or screws, welding, or other permanent means; and it is a further advantage that even marring of surface finish or deposit of explosion products on surfaces of the larger caliber weapon are avoided. The bore and chamber of the larger gun is also protected from injury by climatic conditions.

The preparation of the original weapon for subcaliber operation is accomplished within a few minutes with the weapon in situ in the field, by merely opening the breech, inserting my tube 20 and block 29 into the chamber 11 then inserting the anchor tube 35 at the muzzle and screwing it onto the tube 20 at 36 until the ring 37 and plate 30 are drawn against the muzzle and breech of the tube 10.

Thereafter, a conventional round of the smaller caliber ammunition is inserted through the opening 50, the head 48 being at this time in a position withdrawn a distance by reason of the functioning of the extractors 17 incident to the last operation of the operating handle of the breech mechanism.

When, now, the inserted round is thrust home in the chamber 21, or nearly so, the sleeve 46 and its head and flange 49 are carried forwardly, the flange 49 pushing the extractors 17 forward as in their ordinary functioning with full caliber rounds. They consequently release the breech block so that the closing spring (compressed when the breech was opened) may, and does move the breech block to closed position. In this movement of the block its upper bevelled edge will cam the live round snugly into the chamber 21, and the firing pin will move with the block into alinement with the primer of the small round and stop there. The firing mechanism having been cocked by the breech mechanism, the subcaliber round may now be fired at any time by the usual manual means provided in the original mechanism.

Upon firing, the round functions normally, the projectile passing through the bore 22 with usual rotation, acceleration, and velocity values of the round in proportion to the shortened barrel, and with ample clearance in the anchor tube to avoid impairment of the flight characteristics of the projectile.

There will be a moderate recoil involving movements which will be of an extent only a small part of those produced by the full caliber ammunition for the larger gun, and the summary movement will be insufficient to operate the breech

block. Consequently, after each subcaliber round is fired, it is necessary to open the breech by the usual manual means forming part of the standard equipment of the larger caliber gun.

- 5 In the breech-opening operation of the larger gun, the breech block is drawn rearwardly and downward to clear the breech of the tube 20, and at the same time the extractors 17 are actuated so as to force the flange 49 and sleeve 46 rearwardly, and this is usually accomplished with sufficient speed to throw the sleeve 46 rearwardly with considerable momentum, until stopped by striking of the forward end of the slot 47 against the segment portion of the block 29. The subcaliber cartridge case being engaged loosely through the opening 50, this rapid movement will also cause propulsive ejection of the extracted case of the spent round so that the sleeve 46 becomes a combined extractor and ejector.
- 10 The opening and closing operations of the breech also effect cocking of the firing mechanism as before indicated so that after ejection of the empty case, the loading and firing procedure may be repeated with another live round, the closing operation being automatic in the 75 mm. type of mechanism.

20 The plate 30 performs a most important function in the organization presented, and by fitting to the chamber wall on closing of the breech, largely obviates the need for strong supports or expanding wedges within the tube 10. The principal purposes of the bushings 42 and ring 37 are to afford rigidity of the tubing 35 in the tube 10, to prevent rotation of the inserted parts, and to keep 25 the tubes 20 and 35 in good alinement. That is to say, the plate 30 enables the breech block of the larger weapon, by adequate pressure on the base of the inserted subcaliber cartridge case, to press the latter and also the tube 20 forwardly 30 to a snug fit of the jacket 26 and adapter ring 28 in the chamber 11, and at the same time to position the head 48 in cooperative relation to the extractors 17. The fact should also be appreciated that the provision of the sliding extractor 35 and ejector on the subcaliber weapon, and the provision thereon of a head portion shaped to function with the larger caliber extractor devices, is capable of embodiment in other construction 40 of subcaliber guns coordinated with the breech closure and firing mechanism of the larger weapon in which it is inserted.

45 In this respect the extractor is the most important feature of the invention.

The invention may be adapted to other forms 50 of breech closures, with advantages corresponding to those evident in the particular embodiment shown, as well as others, and while I have disclosed this particular device with great particularity it will nevertheless be understood that 55 it is purely exemplary and that various modifications of construction, arrangement and combination of parts, substitution of materials, and substitution of equivalents, mechanical and otherwise, may be made without departing from the spirit of the invention set forth in the appended claims, wherein I claim:

- 60 1. A subcaliber device for a large caliber gun having a chamber, bore and cartridge case extractors; comprising a barrel chambered and bored to receive conventional small caliber ammunition rounds, means to fix the barrel in the large caliber gun whereby the head of a cartridge case of a round loaded in said barrel will be in the same plane as would the head of a cartridge 65 case of full size ammunition round loaded in the

chamber of the said gun; said means comprising a transversely relieved part of the upper part only of the breech end of the barrel extending forwardly a limited distance from the breech face of the barrel, a transverse upwardly presented rib on said relieved part spaced below the chamber wall of the large caliber gun within the longitudinal limit of the barrel, and a separate vertical planiform plate having a thickness and extent to lie against the breech face of the large caliber gun and across the upper part of the chamber in said gun aligned with said plane, said plate lying above the said extractors and having an integral block on its forward side to extend into the chamber of said gun and shaped to fit the wall of the latter and the said relieved part of the barrel, said block having a transverse groove on its under side to receive said rib separably, whereby when the barrel is assembled to the said gun the plate and block and barrel are locked together and the latter is held against forward movement in the gun, means to hold the barrel against rearward movement in the gun, and a reciprocable member on said barrel, including a head shaped to lie against the said breech face of the gun below said plate, having a rabbeted opening to receive loosely a subcaliber round inserted in the chamber of the barrel, said head having also a lateral flange portion corresponding to the rim of a large caliber round for the gun, whereby said extractors may draw said recipro-

cable member rearwardly to extract a subcaliber cartridge from said barrel.

2. The structure of claim 1 wherein said barrel has an additional exterior relieved face extending forwardly from its breech face beyond and before the said plate and block, the relieved surface being concentric with the axis of the barrel, said reciprocable member including a forward extension slidable over said relieved face and to a forward position with its head in the said plane, and having at the forward part of said extension a lateral part normally spaced forwardly of the block arranged to engage the said block after a given rearward movement of the reciprocable member to limit withdrawal.

WILLIAM SUMMERBELL.
